UNITED STATES PATENT OFFICE

JOHN J. TINKLEPAUGH, OF LIVINGSTON, NEW YORK.

APPLE-SIZING MACHINE.

Application filed October 11, 1923. Serial No. 667,977.

To all whom it may concern:

Be it known that I, JOHN J. TINKLEPAUGH, citizen of the United States, and resident of Livingston, in the county of Columbia and State of New York, have invented certain new and useful Improvements in Apple-Sizing Machines, of which the following is a specification.

The general object of my invention is to provide an improved machine for continuously separating apples of varying sizes into lots or grades with the apples in each such lot or grade of approximately the same size, and different in size from the apples in the other lots.

The various features of novelty which characterize my invention are pointed out with particularity in the claims annexed to and forming a part of this specification. For a better understanding of the invention, however, advantages possessed by it and specific objects obtained with its use reference should be had to the accompanying drawings and descriptive matter in which I have illustrated and described a preferred embodiment of the invention.

The apple grading machine illustrated and described herein is generally similar to a machine heretofore devised and successfully used for grading or sizing peaches and oranges, but in the prior machine the rolls corresponding to those herein, marked C and D, were smooth rolls. The use of smooth rolls, while satisfactory in the case of articles like oranges or peaches which are approximately round or ellipsoidal in shape, cannot be effectively employed with apples because of the shape of their ends and particularly of their stem ends. To convert the orange and peach grading machine with its smooth rolls into an apple grader it was first proposed to simply corrugate the rolls as illustrated herein, so that the space between the cooperating pair of rolls C and D is divided into a plurality of pockets each having a sort of polygonal outline in plan, such pockets are well adapted for the purpose of grading objects shaped as apples are, but the machine thus formed failed in practical operation because of the frequent tendency of the apples to pile up over the sizing pockets and to be carried by the conveyor past the discharge chutes

intended to receive the apples passing between the rolls. In attempting to overcome this difficulty and after considering and experimenting with various expedients devised to that end, I discovered that the difficulty was almost entirely due to the lodging of a comparatively small apple immediately above a reduced portion c' of a roll C, with a consequent arching of a number of apples over the sizing pocket in front, and then discovered that such lodgment could be prevented by providing the guard finger L' which extend into the spaces between the spool portions of the rolls C as illustrated and described, so that no apple large enough to give rise to any arching effect can come to rest on top of a reduced roll portion c' when the apples are initially fed onto the conveyor or subsequently, but must pass as it should into the sizing pocket ahead.

While in accordance with the provisions of the statutes, I have illustrated and described the best form of my invention now known to me it will be apparent to those skilled in the art that changes may be made in the form of the apparatus disclosed without departing from the spirit of my invention as set forth in the appended claims.

Of the drawings:

Fig. 1 is an elevation in section on the line 1—1 of Fig. 2;

Fig. 2 is a somewhat diagrammatic partial plan of the apparatus shown in Fig. 1;

Fig. 3 is a partial section on the line 3—3 of Fig. 1;

Fig. 4 is a section on the line 4—4 of Figs. 2 and 5; and

Fig. 5 is a plan view of a portion of the apparatus shown in section in Fig. 4.

The machine shown in the drawings comprises a stationary framework A in which is mounted a sizing or grading conveyor comprising the rollers C and D and chains B. The shafts C² of the rolls C are journaled at their ends in corresponding links of the chains B. The ends of the shafts C² form pivotal supports for links or swinging arms E in which the ends of the shafts D² of the rollers D are journaled, there being a roll D supported in this manner at the rear of each roll C having reference to the direction of movement of the conveyor

which is that indicated by arrows in Figs. 1 and 2.

The chains B of the conveyor run over suitable sprocket wheels F, F', F² and F³, and a track G is provided for guiding the chains B and thereby the rolls C in the active portion of the conveyor travel which is from the sprocket wheel F to the sprocket wheel F². Another track composed of sections H, H', H², H³, is provided for the rolls D in their travel from the sprocket wheels F to the sprocket wheels F³. The track section H extends between the sprocket wheels F and F' and is upwardly inclined and parallel to and alongside the corresponding portion of the track G, so that in this portion of the conveyor path, the axes of the rolls C and D all lie in the same upwardly inclined plane. The track section H' is inclined downwardly away from the corresponding portion of the track G so that in the corresponding portion of the conveyor path of travel, the rolls D which rest on the track section H' move below the path of travel of the roll D by an amount progressively increasing with the distance from the sprocket wheel F'. The track section H² also diverges away from the corresponding portion of the track G from its rear to its forward end, though ordinarily, and as shown, the angular divergence between the track section H² and the track G is less than that between the track section H' and track G. The track section H³ is upwardly inclined with reference to the track G so that at its forward end the rolls D are brought back into the path of travel of the rolls C as the conveyor pass over the sprocket wheel F². As shown, tracks HG and HG' are provided for guiding the movement of the conveyor, including the rolls C as well as the rolls D, in the idle portion of the conveyor path from the sprocket wheel F² to the sprocket wheel F³, and from the latter back to the sprocket wheel F. The rolls C and D are each circumferentially grooved to divide each of them into an axial series of spool portions each of which comprises a cylindrical body and conical end portions. The adjacent conical ends of adjacent spool portions of each roll C and D are separated by roll portions c' and d', respectively, substantially smaller in diameter than the body portion of the spool. The space between each adjacent pair of spool portions of each roll D and the adjacent spool portions of the roll C immediately behind the said roll D, forms an apple receiving pocket which is initially too small to receive and pass any normal sized apple, but which increases in size as the roll D travels along the track sections H' and H² and diverges from the path of travel of the corresponding roll C. In consequence an apple originally received and held in one of these

pockets will drop through the pocket when the size of the latter is increased to the required extent. Apples of different sizes are therefore discharged from the sizing pockets at different points in the travel of the roll D along the track sections H' and H², so that the different chutes K' and K², K³ and K⁴, into which the apples discharged from the sizing pockets are carried by the transverse belt conveyors I and J, receive apples of progressively increasing size. In operation the apples to be graded are fed onto the portion of the grading conveyor between the sprocket wheel F and F'. Ordinarily a suitable feeding mechanism is providing for putting the apples on the grading conveyor at the proper rate, and in a proper distributed manner, but as such feeding mechanism forms no part of the present invention I have not thought it necessary to illustrate any mechanism of the sort herein.

Inasmuch as each roll C and the roll D immediately behind it always have their axes at the same distance apart, the apples do not pass between these rolls, and to prevent apples from lodging in the recesses in and between the upper portions of these rolls, guard members L as shown are each secured at their ends to a corresponding pair of swinging arms or links E. Each guard member L comprises a body portion the top surface of which is approximately tangential to the body portions of the spool portions of the rolls C and D between which the guard is placed. In accordance with the present invention fingers L' are provided at the forward edge of each guard L and extend between the corresponding spool portions of the adjacent roll C each to a point approximately vertically above the corresponding reduced portion c' of the roll when the latter is moving upward from the sprocket wheel F to the sprocket wheel F', i. e. in the feed receiving portion of the path of travel of grading conveyor.

Having now described my invention what I claim as new and desire to secure by Letters Patent, is:

1. The combination with a grading conveyor comprising a series of parallel corrugated rolls extending transversely to the direction of travel of the conveyor and arranged in pairs and means for varying the distance between the adjacent rolls of adjacent pairs of rolls, as the rolls progress in the path of travel of the conveyor, of guards located one between the rolls of each pair and provided with projections extending into the corrugation grooves of one of the rolls of the pair.

2. The combination with a grading conveyor a portion of the path of travel of which is upwardly inclined, said conveyor comprising a series of parallel corrugated

rolls extending transversely to the length of said path and arranged in pairs, and means for varying the distance between the adjacent rolls of adjacent pairs of rolls, as the 5 rolls proceed along a portion of said path following the first mentioned portion, of guards located one between the rolls of each

pair and provided with projections extending into the corrugation grooves of the leading roll of the pair.

Signed at Livingston, in the county of Columbia and State of New York this 8th

10

day of October A. D. 1923.

JOHN J. TINKLEPAUGH.
